UNITED STATES PATENT OFFICE.

CHARLES A. BREWER, OF CHICAGO, ILLINOIS, ASSIGNOR TO CHARLES A. BREWER & SONS, A PARTNERSHIP CONSISTING OF CHARLES A. BREWER, NELSON C. BREWER, KENNETH E. BREWER, AND EVERETT R. BREWER, OF CHICAGO, ILLINOIS.

BOARD-FILLING MACHINE.

1,339,595.

Specification of Letters Patent. Patented May 11, 1920.

Application filed July 2, 1919. Serial No. 308,226.

To all whom it may concern:

Be it known that I, CHARLES A. BREWER, a citizen of the United States, residing at Chicago, in the county of Cook and State of Illinois, have invented certain new and useful Improvements in Board-Filling Machines, of which the following is a specification:

This invention relates to an improved machine for loading or filling what are commonly known as sales boards of the general character illustrated in Letters Patent No. 780,086 to Brewer and Scannell, dated January 17, 1905. In its general character and purpose, the machine of the present invention is similar to the machine forming the subject matter of Letters Patent No. 1,118,098, granted to me November 24, 1914, as assignee of Albert J. Bates. The machine of the last-named patent operates on the principle of curling or rolling up flat strips of paper and depositing them in sockets or apertures provided at pre-determined distances apart in a board or similar article. The machine of my present invention, instead of operating upon flat strips of paper by first curling or rolling them and then depositing them in the sockets or apertures of the board, operates upon straight, folded or plaited and closely compacted strips of paper, first severing from the forward end of a row of strips sections of a length approximating the thickness of the board to be filled, then pushing the severed sections into a row of apertures of the board, the latter being held in receiving position, then shifting the board to present the next row of empty apertures opposite the ends of the strips, then severing from the strips a second row of sections, then pushing these into the second row of apertures, and so on until the group of strips forming one load or charge for the machine has been completely cut and deposited in the apertures of the board. If, at this point, the board is not completely filled, the machine is recharged with strips, and again operated until the board is completely loaded.

The general object of the invention is to do away with the slow and tedious process of filling these boards by hand with folded or plaited strips, and to provide a machine by which the work may be expeditiously and economically performed.

The nature of the present invention, its

principle and mode of operation, and the advantages inhering therein will all be readily understood and appreciated from the following detailed description when considered in connection with the accompanying drawings in which I have illustrated a practical and operative embodiment of the invention, and in which,—

Figure 1 is a side elevation of the machine;

Fig. 2 is a front elevation, with the board-carrier and board to be filled partly broken away to disclose mechanism lying behind the same;

Fig. 3 is a top plan view, broken off near the rear end of the machine;

Fig. 4 is a vertical longitudinal section taken on the line 4—4 of Fig. 3;

Fig. 5 is a vertical transverse section substantially on the line 5—5 of Fig. 3;

Fig. 6 is a vertical transverse section through the upper portion of the machine taken on the line 6—6 of Fig. 3;

Fig. 7 is an enlarged perspective elevation of a portion of the bed and reciprocating pusher or follower, showing also the pawl-and-rack actuating mechanism of the latter;

Figs. 8 and 9 are enlarged vertical sections taken on the line 8—9 of Fig. 3, showing the cutter just before and after severing the forward end portions of a series of strips;

Fig. 10 is an enlarged sectional detail taken on the line 10—10 of Fig. 5;

Fig. 11 is an enlarged sectional detail taken on the line 11—11 of Fig. 5, showing the clutch mechanism;

Fig. 12 is a side elevation, partly broken out and in section of the clutch mechanism shown in Fig. 11;

Fig. 13 is an enlarged detail view showing the lifting and dogging pawls that effect and control the step-by-step upward movement of the board-carrying frame in idle or released position;

Figs. 14 and 15 are fragmentary side elevation views, partly in vertical section, showing the pawl-and-rack feeding mechanism for the pusher or follower and also illustrating automatic mechanism for stopping the machine when the latter is empty and for automatically retracting the pusher-fingers from the path of the strip cutter; and

Fig. 16 is a perspective view illustrating

the folded or plaited and compacted paper strip upon which the machine operates.

The frame of the machine comprises chiefly a pair of parallel skeleton side frame members 20 and a horizontal bed-plate 21 resting upon and connecting the tops of said side frame members. The forward half of the bed-plate 21 is countersunk, as shown in Figs. 4 and 5, and a steel plate 22 is fitted 10 and secured therein by screws 23, this plate 22 having its top surface formed with a series of narrow longitudinal rectangular grooves or channels 24 occupying approximately the full width thereof. The upper 15 surface of the bed-plate 21 in rear of the insert plate 22 is similarly formed with grooves or channels 24' (Fig. 4) the ends of which register accurately with the ends of the channels 24 and form continuations of 20 the latter. In the grooves 24, when the machine is primed or loaded for operation, are seated the folded or plaited strips operated upon, one of these strips being shown in detail at A in Fig. 16. Each strip is of a 25 size to just fill one of the grooves in the plate 22.

Mounted to travel over the bed-plate of the machine is a reciprocating pusher or follower which acts upon the rear ends of 30 the paper strips under a step-by-step forward movement so as to advance the strips first across the path of a transverse cutter, and then cause the strips themselves to push the severed forward sections thereof into the 35 apertures or pockets of the board to be filled, as hereinafter described in detail. This pusher or follower comprises a series of parallel rectangular steel fingers 25 of a size to slidably fit and fill the grooves 24, 24', and an overlying frame by which these 40 fingers are simultaneously actuated. By reference to Fig. 4 it will be noted that the rear ends of the fingers 25 are turned upwardly as shown at 25', and these up-turned 45 ends 25' are engaged behind the transverse member of a U-shaped frame 26, and are confined in place, with capacity for a slight amount of individual lost motion, by a keeper bar or strip 27 overlying and secured 50 to the frame 26 and formed with a down-turned lip 27' (Fig. 4) engaging behind the up-turned ends 25' of the fingers. Referring to Fig. 7, to the under sides of the longitudinal members of the U-frame 26 55 are secured bars 28 formed on their inner edges within tongues 29 slidably engaged with grooves 30 in the bed-plate 21, and formed on their lower sides with rack teeth 31. On the upper side of the cross-bar 27 60 is mounted a handle 27', by which the pusher or follower may be manually retracted preliminary to reloading the machine.

The mechanism for effecting the step-by-step forward feed movement of the pusher 65 is best shown in Figs. 14 and 15, and com-

prises the following parts. Fast on the main drive shaft 32 are a pair of eccentrics 33, each of which actuates a rod or bar 34. This latter is pivotally connected at its forward end to a longitudinally slotted 70 pawl-carrier 35 riding on a pair of studs 36 projecting from the side-frame member 20. On the rear end of the pawl-carrier 35 is a short vertical extension 35', in which is pivoted a pawl 37, the nose of which is 75 normally maintained in engagement with the rack-bar 31 by a spring 38. The to-and-fro travel of the pawl is somewhat in excess of the distance between the working faces of adjacent teeth, and its forward movement 80 advances the pusher a distance equal to that between the working faces of adjacent teeth at each reciprocation. It will be observed that the next to the last tooth of the rack-bar is slightly longer than the other teeth 85 for a purpose hereinafter disclosed.

Between successive advance movements of the paper strips their forward ends are first compressed and then severed by the following mechanism, best shown in Figs. 5, 8, 90 9, 14 and 15. Across the forward end of the bed-plate 22 is formed a groove or channel 39 that intersects the strip-holding grooves 24 and extends below the latter and contains a strip 40 of horn fiber or like relatively soft material forming an abutment block for the edge of the cutter blade, the upper surface of this block being flush with the bottoms of the grooves 24; and overlying the extreme end of the bed-plate, 95 just forwardly of the channel 39 is a fixed bar 41, of triangular form in cross-section, that forms a top wall for the grooves 24 at that point and prevents bending or buckling of the severed strips as they are forced 100 into the holes of the board to be filled. Also overlying the bed-plate transversely on the other side of the channel 39 is another bar 42 having a beveled or chambered lower rear edge 42' to facilitate the manual insertion 110 of the forward ends of the paper strips therebeneath in the loading of the machine. Above the bar 42 is a presser-bar 43 that is guided for limited vertical movement by pins or studs 44 set in the bar 42 and passing 115 through holes in the bar 43, said presser-bar 43 having a vertical depending flange 45 overlying the forward edge of the bar 42 and movable down onto the tops of the paper strips lying across the channel 39. 120 The presser-bar 43 is normally upheld by compression springs 46 surrounding the pins 44 between the bars 42 and 43. Above the presser-bar 43 and loosely connected to the latter by headed pins or studs 47 is an 125 actuating bar 48, the ends of which extend between and are guided by uprights 49 and 50 forming vertical extensions of the side-frame members. Compression springs 51 encircling the pins 47 between the bars 48 130

and 43 cushion the downward thrust of the former on the latter. Pivoted to the ends of the actuating bar 48 are depending links 52 (Figs. 2, 5 and 10), each of which is guided for vertical reciprocating movement in a guide-block 53 secured to the side-frame and at its lower end carries a roller 54 that lies in the cam groove 55 of a cam disk 56 fast on the main drive-shaft 32. By reference to Fig. 10 it will be observed that the cam groove 55 is formed with approach and departure inclined portions 57 and 58 and with an intermediate dwell portion 59 that coöperates with the roller while the presser-bar is fully down on and holding the paper strips and the cutter is severing them.

For shearing the paper strips the following cutter mechanism is employed. 60 designates the cutter head that extends transversely between and is guided by the vertical extensions 49 and 50 of the side frame members. To this head is adjustably secured the cutter blade 61 by means of 25 clamp-screws 62 passing through vertical slots 63 in the head 60 (Figs. 8 and 9). Ball gudgeons 64 on the ends of the cutter-head are joined through adjustable inclined connecting-rods 65 to ball cranks 66 secured on 30 the ends of the drive shaft 32. A bearing lug 67 pivoted on the cutter-head has sliding engagement with an inclined bearing 68 formed in the inner face of one of the uprights 49 (Figs. 8 and 9); and this, together 35 with the inclined position of the connecting rods 65, gives an oblique or inclined up-and-down movement to the cutter, thus giving a draw cut on the strips severed by the cutter blade.

40 Referring to Fig. 2, at the forward end of the machine is a rectangular frame consisting of vertical side bars 69 and a bottom cross-bar 70. This frame is guided for vertical movement by and between the side 45 frame members and their vertical extensions 50 and also by guide strips 71 overlapping the side bars 69 of the frame. This frame constitutes a holder or carrier for a rectangular metal plate 72 that is hinged at 50 its lower end, at 73, to the frame bars 69 and, in its closed position, fits between the latter. This metal plate, in turn constitutes the holder or direct support for the board to be filled, identified by the reference 55 numeral 74. The plate 72 is formed with a number of holes 75 carrying board positioning pins 76, preferably four in number, that enter holes in the board to be filled and accurately position and hold said 60 board on the plate. Since the machine is adapted to fill boards of widely varying sizes and capacities, the plate 72 is provided with a large number of holes 75 at varying distances from its edges so as to 65 accommodate any size of board. At the lower ends of the vertical frame bars 69 are forwardly projecting brackets 77 (Fig. 4) that form rests for the plate 72 in the open position of the latter when the board is to be applied thereto. The plate 72 is securely held in upright or closed position by cleats 78 secured thereto and overlapping the outer sides of the frame bars 69 and by latches 79 pivoted to the upper ends of the frame bars 69 and overlapping the upper corners 75 of the plate 72. Near the upper end of said plate is secured a handle bar 80 by which the plate is readily swung up and down on its hinges 73. On one of the frame bars 69 is a scale 81 coöperating with a pointer 82 fixed on the frame, the divisions of the scale corresponding with the horizontal rows of holes in the board to be filled, and the pointer, which is located in the horizontal plane of the hole-filling mechanism, 85 showing the extent to which the board has been filled at any period in the operation of the machine.

The rear sides of the vertical frame bars 69 are formed as racks 83 (Figs. 4 and 13), 90 which form part of a mechanism for effecting the step-by-step upward movement of the frame and plate carrying the board to be filled, so as to present successive horizontal rows of holes opposite the filling mechanism. On the drive shaft 32 are a pair of eccentrics 84 on which are journaled lifting pawls 85 to coact with the racks 83; and below the pawls 85 are pivoted a pair of dogging pawls 86 that likewise co-act with the racks 83 to hold the latter raised while the lifting pawls are descending for a fresh engagement with the racks. These dogging pawls are urged into engagement with the racks by tension springs 87 connecting the tails of the pawls with a fixed member of the frame. Secured to the hub of each lifting pawl 85 is a depending bent finger 88, the lower end of which lies opposite the tail of the underlying dogging pawl and operates 105 to throw the latter out of engagement with the rack when the board and its carrying frame are to be lowered. Reverting to Fig. 2, the lowermost position of the board-carrying frame is determined by forwardly projecting stop-lugs 89 on the frame bars 69 which come to rest on a pair of adjustable stops herein shown as screws 90 threaded through inwardly projecting angle brackets 91 secured to the side frame members. At 110 each revolution of the drive shaft 32, the frame and plate carrying the board to be filled are raised the distance of one tooth of the rack 83, this occurring during the idle or return movement of the pawl-and-rack feed mechanism of the pusher, and during the forward or working stroke of the latter the lifting pawls 85 are returning for a 115 fresh engagement with the racks 83.

The weight of the board and board-carry- 130

ing plate and frame is partially counterbalanced by means of a weight 92 (Fig. 4) attached to one end of a strap 93 which extends over a pulley 94 and at its other end is attached to the rear side of the transverse frame bar 70. This counter-balancing device is not essential, but facilitates steadiness of operation of the machine and is preferably employed.

10 On one end of the drive shaft 32 is a belt pulley 95 which is loose on said shaft and is normally clutched to the latter by a spring-actuated sliding pin 96 adapted to be withdrawn once during each revolution 15 of the shaft by a wedge-shaped finger 97 lying in a groove 98 of a collar 99 that is fixed on the shaft along side of the pulley 95 and carries the sliding pin 96; said finger being pivoted at 100 (Fig. 11) and normally upheld so as to intersect a transverse 20 groove 101 of the finger 96 by means of a compression spring 102 stepped on a stationary bracket 103 and acting against a collar 104 fast on a rod 105 pivoted at 106 25 to the finger and extending through a guide aperture in the bracket 103. This type of clutch is an old and well known clutch employed on punch presses and similar machines requiring automatic control of the 30 driving mechanism, and is excellently adapted to the purposes of the present machine. This clutch is controlled by a lever 107 that is fulcrumed at 108 (Figs. 2 and 5) and at one end is articulated to the rod 105 between a pair of buttons 109 on said 35 rod, and on the other side of its fulcrum extends obliquely across the machine frame (Fig. 5) and terminates in a laterally projecting handle 110. When this handle is 40 raised to throw the clutch in and start the machine it rests upon a shoulder 111 of a bent keeper 112 secured to the side frame of the machine; and when the handle is manually or automatically moved off said shoulder, it drops to the bottom of the keeper, as 45 shown in Fig. 1, allowing the spring 102 to disconnect the clutch. As stated, the operation of the machine may be manually arrested at any time by simply throwing the 50 handle of the lever off its rest 111; and this is automatically effected at the extreme inward travel of the pusher or follower when a set of paper strips has been completely loaded into the board by means of a lug 55 113 (Fig. 1) on the side of one of the rack-bars 31 coming into contact with the upper end of a pivoted lever 114, the lower end of which lever lies along side the handle 110 when the latter is in its raised position on the rest 111, whereby the lower end of said 60 lever kicks the handle off its rest. The lever 114 is returned to normal position by the tension spring 115. A tension spring 116 normally holds the handle of the start-

ing and stopping lever engaged with its 65 seat 111.

The machine also includes manually operable means within convenient reach of the operator for arresting the feeds of the pusher and board-carrier in case of faulty 70 operation and also independently of the starting and stopping lever. This mechanism is best shown in Figs. 1, 4, 6 and 13, and comprises the following parts. A bail-shaped member comprising parallel arms 75 117 and a cross-bar 118 is attached at the inner ends of the arms 117 to radial projections 119 on the hubs of the lifting pawls 85 (Fig. 13). This member is normally held in the raised position shown in Figs. 80 1 and 4 by tension springs 120. The cross-bar 118 is connected centrally by a suspended slotted link 121 (Fig. 6) to a hand lever 122 pivoted at one end, at 123, to one of the side frames and at its other end 85 formed with a handle 124 projecting beyond the opposite side frame. The lever 122 is normally maintained in raised position by a tension spring 125. Rigidly secured to and depending from the outer side of each 90 of the pusher feed pawls 37 is a depending bar 126, on one edge of which is a cam incline 127 lying just below a finger 128 that is secured to and projects laterally from each of the arms 117 of the bail-shaped 95 member. When, now, the handle 124 is depressed to an extent sufficient to cause the fingers 128 to wipe over the cam inclines 127 the pawls are rocked out of engagement with the racks 31 of the pusher, and simultaneously the pawls 85 are rocked out of 100 engagement with the racks 83, thus simultaneously arresting both the feed of the stock and the upward travel of the board-holder. If the downward movement of the handle 105 be continued until the fingers 128 reach laterally projecting feet 126' on the lower ends of the bars 126, the tails 88 of the lifting pawls 85 strike the dogging pawls 86, as 110 shown in Fig. 13, and rock the latter out of holding engagement with the racks 83, thus permitting the board-carrier to descend by gravity (retarded by the counter-weight 92) until it comes to rest in its lowermost position with the stop lugs 89 resting on the 115 stops 90.

To aid in loading and priming the machine, there is also employed a manually operated device for clamping the presser-bar 45 onto the forward ends of the paper 120 strips. This device comprises a pair of elbow levers that are pivoted at 129 (Figs. 8 and 9) to the uprights 49, the forwardly projecting arms 130 of said levers lying in transverse notches 131 formed in the upper side of the bar 48, and the upwardly and rearwardly extending arms 132 of said 125 elbow levers being connected by a handle-

bar 133. This manual clamping device is locked in clamping position by a pivoted hook 133' (Fig. 3) engaging with one of the lever arms 132 under the pull of a tension spring 133".

On the upper side of the pusher frame are mounted a pair of longitudinally extending angle bars 134 (Figs. 6 and 7). These bars serve as guides for a thick plate or block 135 that, in the priming of the machine, is laid on the grooved bed-plate after the latter has been loaded with the paper strips, and the forward ends of the latter have been clamped manually by the clamping device last described. This plate or block forms a sort of ironing device and is manually moved several times to and fro over the surface of the bed to flatten the strips down in the grooves of the latter, and is then allowed to rest on the surface of the bed to hold the strips from bowing upwardly. It is preferably made of glass, so as to permit the attendant to see if the strips are properly laid.

On the opposite sides of the pusher frame are also mounted a pair of buffer or recoil devices, the function of which is to quickly retract the forward ends of the pusher fingers from the path of travel of the cutter during the operation of forcing the next to the last and the last rows of strip sections into the board. Each of these devices consists of a spring casing 136 secured to a side member 26 of the pusher frame, a plunger 137 slidably mounted in the casing 136 and having a stem 138 extending through a hole in the rear end of the casing, a coiled compression spring 139 surrounding the stem 138 within the casing, and stop-nuts 140 on the outer end of the stem 138 normally abutting against the outer end of the casing under the thrust of the spring. The function of these devices will be set forth in connection with the description of the complete operation of the machine.

Describing now the operation of the machine, the folded and compacted paper strips are first loaded by hand into the longitudinal grooves of the bed-plate, one strip lying in each groove, and the forward ends of the strips extending substantially flush with the forward end of the bed. The strips are then temporarily clamped in place by raising the handle 133 of the manual clamping device, and the ironing block 135 is moved over the bed a few times between the guide bars 134 and then brought to rest to flatten and hold the strips down in the grooves. At this time the pusher is in its fully retracted position, with the forward ends of the pusher fingers lying behind the rear ends of the paper strips. The manual clamp is then released.

Either before or after the loading of the

paper strips in the bed of the machine as described, an empty board to be filled is properly mounted upon the board-carrying plate 72, for which purpose said plate is swung outwardly and downwardly on its hinges 73 to a position of rest on the foot 70 brackets 77. By means of the pins 76 the board is mounted and accurately positioned on the inner face of the carrying plate 72 so that, when the plate is swung to vertical position and locked therein by the cleats 78 and latches 79, the topmost row of holes will lie exactly opposite and in register with the forward ends of the paper strips as they lie in the bed-plate of the machine.

The clutch is then thrown in and the 80 knife descends, severing from the forward ends of the strips a row of short sections each of a length slightly less than the thickness of the board to be filled. While the knife is thus severing the strips, the pusher 85 feed pawls are moved backwardly into engagement with the foremost teeth of the racks 31; and on the forward or advance movement of the pawls 37 the pusher is moved forwardly the length of one tooth 90 which corresponds to the length of the sections successively severed by the cutter. On this first advance movement of the pusher the severed strip sections of the first row are pushed by the strips behind them into the 95 top row of holes in the board. At the conclusion of this operation the board feeding pawls 85 make an upward movement, raising the board and its holder to the extent of one tooth of the racks 83, which is equal to the distance between successive horizontal rows of holes in the board, thus bringing another row of empty holes into receiving position. The knife again descends severing another row of short strips which are 100 pushed into the second row of holes upon the second advance movement of the pusher, and this cycle of operation is continued until the cutter has made its last strip severing stroke. At this point the pusher feed 110 pawls 37 engage with the next to the last teeth of the racks 31 which, it will be remembered, have been described as of extra length; so that, on the next forward or feed movement of the pusher the forward ends 115 of the pusher fingers, as shown in Fig. 14, advance slightly beyond the vertical plane of the cutting edge of the knife 61. The purpose of this is to force the last row of strip sections slightly beyond the cutting path of the knife so as to avoid filling and clogging the small passages at the forward end of the bed and overlying the strip 41 with paper chips or shavings. The tips of the pusher fingers having been advanced 120 slightly beyond the cutting path of the knife, it is, of course, very necessary to retract said fingers before the knife descends;

and this is done automatically by the plungers 137 of the buffer devices coming into contact, during the last part of this stroke, with the base blocks of the uprights 49, 5 whereby the springs 138 act promptly to retract the pusher sufficiently to carry the tips of the fingers back behind the path of the cutter. In this connection it is noted that the parts are so timed that the feed pawls 10 37 are retracted to permit the retraction of the pusher by the buffer springs before the edge of the knife in its descent reaches the plane of the pusher fingers.

The last row of strip sections is forced 15 into the board by the fingers themselves on the last forward or feed movement of the pusher, as clearly shown in Fig. 15. Here, again, the buffer devices act to promptly throw back the pusher to a position in which 20 the tips of the fingers are behind the path of the cutter. It will thus be seen that these buffer devices perform an important function in the machine in connection with the feeding in of the last row of strips by enabling the latter to be fed into the board by 25 the pusher fingers themselves without injury to either the fingers or the sharp edge of the cutter.

As soon as the last row of strips has been 30 loaded into the board, the machine is automatically stopped by the lug 113 striking the lever 114 and throwing the starting and stopping lever 110 into stopping position, as shown in Fig. 15. If the board is not 35 fully loaded with one charging of the machine, the bed plate is recharged with strips in the manner already disclosed and the operation of the machine continued until the board has been filled. Of course, the machine 40 may be instantly stopped at any time manually by simply throwing the lever handle 110 off its rest 111; or by depressing the handle lever 124, both the feeding mechanisms of the pusher and of the board-carrier 45 may be arrested; and by depressing the handle 124 to its lowest position, the dogging pawls 86 are withdrawn, and the board and its carrying frame and plate are dropped to initial or starting position, 50 which is usually done when a filled board is to be removed and an empty board to be put in place. In the event that the machine fails to operate perfectly through buckling of the strips or any other cause, its operation 55 may be instantly arrested by manipulation of either of the control levers. I have found by experience that, owing to the small size and fragile and delicate character of the stock operated upon, the various co-operating parts of the machine and particularly those parts effecting and controlling 60 passage of the strip sections into the board, have to be made with exceeding accuracy and fineness of measurement; but when so 65 made the machine operates accurately and

satisfactorily, and will fill a thousand hole board in about two minutes,—an operation requiring several hours' time when manually performed.

It is evident that the machine shown and 70 described herein might be changed to a considerable extent in respect to detail features and organization without involving any departure from the operative principles employed or lessening the efficiency and utility 75 of the machine for its designed purpose. Hence, I do not limit the invention to the practical mechanical embodiment thereof herein set forth by way of illustration, but reserve all such variations and modifications 80 as fall within the spirit and purview of the appended claims.

I claim:

1. In a machine of the character described, the combination of means for holding a perforated board, a grooved bed-plate disposed in a plane substantially normal to the plane of said board when the latter is held by said holding means and adapted to support a plurality of paper strips in the 85 grooves thereof, and means for pushing said strips endwise into the perforations of said board.

2. In a machine of the character described, the combination of means for holding a perforated board, means for supporting a plurality of paper strips in a plane substantially normal to the plane of said board when the latter is held by said holding means, means for cutting said strips 95 crosswise into a plurality of sections, and means for successively pushing said strip sections endwise into the perforations of said board.

3. In a machine of the character described, the combination of means for holding a perforated board, means for supporting a plurality of paper strips in a plane substantially normal to the plane of said board when the latter is held by said holding means, means for clamping said strips on said support, means for cutting said strips crosswise adjacent to said clamping means into a plurality of sections, and means for successively pushing said strip 105 sections endwise into the perforations of said board.

4. In a machine of the character described, the combination of means for holding a board containing rows of perforations, 110 means for supporting a row of paper strips in a plane substantially normal to the plane of said board when the latter is held by said holding means, means for cutting said row of strips crosswise, means for advancing 115 said row of strips after each cutting operation to force the severed strip sections into a row of perforations of said board, and means for moving said board-holding means to bring the empty rows of perfora- 120 125 130

tions successively opposite the forward end of said row of strips.

5. In a machine of the character described, the combination of means for holding a board containing rows of perforations, 5 means for supporting a row of paper strips in a plane substantially normal to the plane of said board when the latter is held by said holding means, means for clamping said 10 row of strips adjacent to their forward ends on said support, means for cutting said row of strips crosswise just in advance of said clamping means, means for advancing said row of strips after each cutting operation 15 to force the severed strip sections into a row of perforations of said board, and means for moving said board-holding means to bring the empty rows of perforations successively 20 opposite the forward end of said row of strips.

6. In a machine of the character described, the combination of a bed-plate having a series of parallel longitudinal grooves in its upper surface adapted to contain 25 paper strips, means for supporting a perforated board opposite one end of said bed-plate, and a pusher slidably mounted on said bed-plate and formed with a series of 30 pusher fingers slideable in said grooves and operating to force said paper strips end- 35 wise into the perforations of said board.

7. In a machine of the character described, the combination of a bed-plate having a series of parallel longitudinal grooves 35 in its upper surface adapted to contain paper strips, means for supporting a perforated board opposite one end of said bed-plate, a guide-bar transversely overlying 40 said grooves adjacent to the forward end of said bed-plate, and a pusher slidably mounted on said bed-plate and formed with a series of 45 pusher fingers slideable in said grooves and operating to force said paper strips endwise through said grooves and beneath 50 said guide-bar into the perforations of said board.

8. In a machine of the character described, the combination of a bed-plate having a series of parallel longitudinal grooves 50 in its upper surface adapted to contain paper strips, means for supporting a perforated board opposite one end of said bed-plate, a cutter operative to sever short sections 55 of said strips from the forward ends of the latter, and a pusher slidably mounted on said bed-plate and formed with a series of pusher fingers slideable in said grooves and operating intermittently to force said strips endwise beneath said cutter and simultaneously 60 force the severed sections of said strips into the perforations of said board.

9. In a machine of the character described, the combination of a bed-plate having a series of parallel longitudinal grooves 65

in its upper surface adapted to contain paper strips, means for supporting a perforated board opposite one end of said bed-plate, a vertically movable clamp-bar transversely overlying said bed-plate adjacent to the forward end of the latter, a cutter operative to sever short sections of said strips from the forward ends of the latter just in advance of said clamp-bar, and a pusher 70 slidably mounted on said bed-plate and formed with a series of pusher fingers slideable in said grooves and operating intermittently to force said strips endwise beneath said clamp-bar and cutter and simultaneously 75 force the severed sections of said strips into the perforations of said board.

10. In a machine of the character described, the combination of a bed-plate having a series of parallel longitudinal grooves in its upper surface adapted to contain paper 85 strips, means for supporting a perforated board opposite one end of said bed-plate, a guide-bar transversely overlying said grooves adjacent to the forward end of said bed-plate, a vertically movable clamp-bar 90 transversely overlying said bed-plate just in advance of said guide-bar, a cutter operative to sever short sections of said strips from the ends of the latter just in advance of 95 said clamp-bar, and a pusher slidably mounted on said bed-plate and formed with a series of pusher fingers slideable in said grooves and operating intermittently to force said strips endwise beneath said guide-bar, clamp-bar and cutter and simultaneously 100 force the severed sections of said strips into the perforations of said board.

11. In a machine of the character described, the combination of a longitudinally grooved bed-plate adapted to contain paper 105 strips, means for advancing said strips step-by-step through said grooves, a cutter operative to successively sever short sections from the forward ends of said strips, a board-holder mounted opposite the forward 110 end of said bed-plate, and means for imparting a step-by-step movement to said board-holder across the end of said bed-plate.

12. In a machine of the character described, the combination of a longitudinally grooved bed-plate adapted to contain paper strips, a pusher for advancing said strips through said grooves, a cutter operative to successively sever short sections from the forward ends of said strips, a board holder 120 mounted opposite the forward end of said bed-plate, means for effecting successive forward movements of said pusher, and means for effecting successive movements 125 of said board-holder across the end of said bed-plate alternately with the movements of said pusher.

13. In a machine of the character described, the combination of a longitudinally 130

grooved bed-plate adapted to contain paper strips, a pusher for advancing said strips through said grooves, a cutter operative to successively sever short sections from the 5 ends of said strips, a board-holder mounted opposite the forward end of said bed-plate, pawl-and-rack mechanism for effecting successive forward movements of said pusher, and pawl-and-rack mechanism for effecting 10 successive movements of said board-holder across the end of said bed-plate alternately with the movements of said pusher.

14. In a machine of the character described, the combination of a longitudinally 15 grooved bed-plate adapted to contain paper strips, a pusher for advancing said strips through said grooves, means for effecting a step-by-step movement of said pusher, and manually operable means for arresting the 20 operation of said pusher, actuating means.

15. In a machine of the character described, the combination of a longitudinally grooved bed-plate adapted to contain paper strips, a pusher for advancing said strips 25 through said grooves, a board-holder mounted opposite the forward end of said bed-plate, means for effecting a step-by-step movement of said board-holder across said bed-plate, and manually operable means for 30 arresting the operation of said board-holder actuating means.

16. In a machine of the character described, the combination of a longitudinally grooved bed-plate adapted to contain paper 35 strips, a pusher for advancing said strips through said grooves, a cutter operative to successively sever short sections from the forward ends of said strips, a board-holder mounted opposite the forward end of said 40 bed-plate, means for effecting successive forward movements of said pusher, means for effecting successive movements of said board-holder across the end of said bed-plate alternately with the movements of 45 said pusher, and manually operable means for arresting the operation of both said pusher actuating means and said board-holder actuating means.

17. In a board-filling machine, means for 50 supporting a board in position to be filled, comprising a frame, a plate hinged in said frame to swing into and out of the plane of the latter, and means for mounting the board in fixed position on one side of said 55 plate.

18. In a board-filling machine, means for supporting a board in position to be filled, comprising a frame, a plate hinged in said frame and formed with holes at varying 60 distances from its edges, and pins adapted to be mounted in any of said holes and to enter holes formed in the board, whereby said plate is adapted to support boards of varying sizes.

65 19. In a board-filling machine, means for

supporting a board in position to be filled, comprising a generally U-shaped frame, a rectangular plate hinged at its lower end in said frame, and means for mounting the board in fixed position on one side of said 70 plate.

20. In a board-filling machine, means for supporting a board in position to be filled, comprising a generally U-shaped frame having at its lower end a forwardly projecting 75 bracket, a rectangular plate hinged at its lower end in said frame and adapted, when swung forwardly and downwardly, to rest on said bracket, and means for mounting the board in fixed position on the rear side 80 of said plate.

21. In a machine of the character described, the combination with a horizontal longitudinally grooved bed-plate to hold paper strips, means for forcing said strips 85 through the grooves of said bed-plate, and means for cutting said strips into short sections, of a vertical slideway opposite the delivery end of said bed-plate, a board-holder mounted in said slideway, and means 90 for effecting a step-by-step upward travel of said board-holder in a slideway.

22. In a machine of the character described, the combination with a horizontal longitudinally grooved bed-plate to hold paper strips, means for forcing said strips through the grooves of said bed-plate, and means for cutting said strips into short sections, of a vertical slideway opposite the 95 delivery end of said bed-plate, a board-holder mounted in said slideway, pawl-and-rack mechanism for effecting an intermittent upward travel of said board-holder in said 100 slideway, and a counter-balance for said board-holder.

105 23. In a board-filling machine, the combination of a vertical slideway, a frame for supporting the board to be filled mounted in said slideway, a vertical rack on said frame, a lifting pawl engaged with said rack, a 110 dogging pawl also engaged with said rack, and manually operable means acting to first disengage said lifting pawl from said rack and, upon a further movement, to disengage said dogging pawl from said rack.

115 24. In a board-filling machine, the combination of a vertical slideway, a frame for supporting the board to be filled mounted in said slideway, a vertical rack on said frame, a lifting pawl engaged with said rack, a 120 dogging pawl also engaged with said rack, manually operable means for rocking said lifting pawl out of engagement with said rack, and an extension-piece on said lifting pawl operating, when the latter has been retracted a certain distance from the rack, to force said dogging pawl out of engagement with the rack and allow said frame to drop.

125 25. In a board-filling machine, the combination of a machine frame, a shaft jour-

- naled therein, a vertical slideway on one end of said machine frame, a board - carrier mounted in said slideway, a vertical rack on said board - carrier, an eccentric on said shaft, a lifting pawl mounted on and actuated by said eccentric and engaged with said rack, a dogging pawl also engaged with said rack, and manually operable means for rocking said lifting pawl out of engagement 5 with said rack.
26. In a board-filling machine, the combination of a machine frame, a shaft journaled therein, a vertical slideway on one end of said machine frame, a board - carrier mounted in said slideway, a vertical rack on said board - carrier, an eccentric on said shaft, a lifting pawl mounted on and actuated by said eccentric and engaged with said rack, a dogging pawl also engaged with said 15 rack, manually operable means for rocking said lifting pawl out of engagement with said rack, and an extension-piece on said lifting pawl operating, when the latter has been rocked a certain distance from the rack, 20 to force said dogging pawl out of engagement with the rack and allow said board-carrier to drop.
27. In a machine of the character described, the combination of a longitudinally 30 grooved bed-plate adapted to contain strips of paper in the grooves thereof, and a device for forcing said strips endwise through said grooves, including a bar transversely overlying said bed-plate, and a series of 35 pusher fingers lying in said grooves and at their rear ends operatively connected to said bar.
28. In a machine of the character described, the combination of a longitudinally 40 grooved bed-plate adapted to contain strips of paper in the grooves thereof, and a device for forcing said strips endwise through said grooves, including a bar transversely overlying said bed-plate and formed with a 45 longitudinal groove in its under side, a series of pusher fingers lying in said grooves and having up-turned rear ends confined in the groove of said bar, and a handle on said bar for manually retracting said strip-for- 50 ing device.
29. In a machine of the character described, the combination with a machine frame, and a longitudinal grooved bed-plate adapted to hold strips of paper in the 55 grooves thereof, of a pusher slidably mounted in said grooves, a rack on said pusher, a pawl-carrier reciprocably mounted on said frame, a pawl pivoted on said pawl-carrier, a spring urging said pawl into engagement 60 with said rack, and means for reciprocating said pawl carrier.
30. In a machine of the character described, the combination of a machine frame, a shaft journaled in said frame, a longitudinally 65 grooved bed-plate on said frame
- adapted to hold strips of paper in the grooves thereof, a pusher slidably mounted on said frame and having pusher fingers lying in said grooves, a rack on said pusher, a pawl-carrier reciprocably mounted on 70 said frame, a pawl pivoted on said pawl-carrier, a spring urging said pawl into engagement with said rack, an eccentric on said shaft, and an eccentric rod connecting said eccentric with said pawl-carrier. 75
31. In a machine of the character described, the combination with a machine frame, and a longitudinally grooved bed-plate adapted to hold strips of paper in the grooves thereof, of a pusher slidably mounted 80 on said frame and having pusher fingers lying in said grooves, a rack on said pusher, a pawl-carrier reciprocably mounted on said frame, a pawl pivoted on said pawl-carrier, a spring urging said pawl into engagement 85 with said rack, means for reciprocating said pawl-carrier, a cam on said pawl, and a hand lever acting through said cam to disengage said pawl from said rack.
32. In a machine of the character described, the combination with a machine frame, and a longitudinally grooved bed-plate adapted to hold strips of paper, of a pusher slidably mounted on said frame and having pusher fingers lying in said grooves, 90 means for imparting an intermittent forward travel to said pusher, a cutter blade transversely overlying said bed-plate and operating to cut said strips into short sections as they are intermittently advanced by 95 said pusher fingers across the path of movement of said blade, and means for automatically retracting said pusher when the forward ends of said pusher fingers have passed across the path of said blade. 100
33. In a machine of the character described, the combination with a machine frame, and a longitudinal grooved bed-plate adapted to hold strips of paper, of a pusher slidably mounted on said frame and having 110 pusher fingers lying in said grooves, means for imparting an intermittent forward travel to said pusher, a cutter blade transversely overlying said bed-plate and operating to cut said strips into short sections as 115 they are advanced by said pusher fingers across the path of movement of said blade, and a resilient buffer carried by said pusher and operating to automatically retract the latter when the forward ends of said pusher 120 fingers have passed across the path of said blade.
34. In a machine of the character described, the combination with a machine frame having stop members, and a longitudinally grooved bed-plate adapted to hold strips of paper, of a pusher slidably mounted on said frame and having pusher fingers lying in said grooves, pawl-and-rack mechanism for imparting an intermittent forward 125
- 130

travel to said pusher, a cutter blade transversely overlying said bed-plate and operating to cut said strips into short sections as they are advanced by said pusher fingers 5 across the path of movement of said blade, and a pair of spring-backed plungers carried on opposite sides of said pusher respectively and co-operating with said stop members to retract said pusher when said pusher 10 fingers have passed across the path of said blade.

35. In a machine of the character described, the combination with a machine frame, and a longitudinally grooved bed-plate adapted to hold strips of paper, of a pusher slidably mounted on said frame and having pusher fingers lying in said grooves, a cutter blade transversely overlying said bed-plate and operating to cut said strips into short sections as they are advanced by 15 said pusher fingers across the path of movement of said blade, and mechanism for imparting an intermittent forward travel to said pusher and including means for causing said pusher fingers to force the last row of strip sections across and beyond the path of said blade.

36. In a machine of the character described, the combination with a machine frame, and a longitudinally grooved bed-plate adapted to hold strips of paper, of a pusher slidably mounted on said frame and having pusher fingers lying in said grooves, a cutter blade transversely overlying said bed-plate and operating to cut said strips into short sections as they are advanced by 30 said pusher fingers across the path of movement of said blade, and pawl-and-rack mechanism for imparting an intermittent forward travel to said pusher, said rack including a tooth of extra length whereby said pusher fingers are caused to force the last row of strip sections across and beyond the path of said blade.

45. 37. In a machine of the character described, the combination of a longitudinally grooved bed-plate adapted to hold plaited strips of paper, and a manually operable ironing block resting upon said bed-plate to press and hold said strips down in the 50 grooves of said bed-plate.

38. In a machine of the character described, the combination of a longitudinally grooved bed-plate adapted to hold plaited strips of paper, and a presser-bar transversely overlying the forward end of said bed-plate and serving to clamp the forward ends of said strips in the grooves of said bed-plate.

60. 39. In a machine of the character described, the combination of a longitudinally grooved bed-plate adapted to hold plaited strips of paper, a presser-bar transversely overlying the forward end of said bed-plate

and serving to clamp the forward ends of 65 said strips in the grooves of said bed-plate, and a manually operable ironing block resting upon said bed-plate to press and hold said strips down in said grooves.

40. In a machine of the character described, the combination of a longitudinally grooved bed-plate adapted to hold plaited strips of paper, a presser-bar transversely overlying the forward end of said bed-plate and serving to clamp the forward ends of 70 75 said strips in the grooves of said bed-plate, parallel guide-bars disposed along the sides of said bed-plate, and a manually operable ironing block resting upon said bed-plate between said guide-bars to press and hold 80 said strips down in said grooves.

41. In a machine of the character described, the combination of a longitudinally grooved bed-plate adapted to contain strips of paper, a pusher for advancing said strips 85 through the grooves of said bed-plate, means for imparting a step-by-step forward movement to said pusher, and automatic means for arresting the operation of said machine on the last forward movement of said 90 pusher.

42. In a machine of the character described, the combination of a longitudinally grooved bed-plate adapted to contain strips 95 of paper, a pusher for advancing said strips through the grooves of said bed-plate, a contact-lug on said pusher, means for imparting a step-by-step forward movement to said pusher, and means actuated by said contact-lug on the last forward movement 100 of said pusher for arresting the operation of said machine.

43. In a machine of the character described, the combination of a longitudinally grooved bed-plate adapted to contain strips 105 of paper, a pusher for advancing said strips through the grooves of said bed-plate, a contact-lug on said pusher, means for imparting a step-by-step forward movement to said pusher, a starting and stopping lever, 110 and means actuated by said contact-lug on the last forward movement of said pusher for throwing said lever to stopping position.

44. In a machine of the character described, the combination of a longitudinally 115 grooved bed-plate adapted to contain strips of paper, a pusher for advancing said strips through the grooves of said bed-plate, means for imparting a step-by-step forward movement to said pusher, a starting and stopping 120 lever, a spring urging said lever to stopping position, a rest supporting said lever in starting position against the action of said spring, and means actuated by said pusher on its last forward movement for dislodging 125 said lever from said rest.

CHARLES A. BREWER,
